CLAIM

The ornamental design for a candle holder, as shown and described.

DESCRIPTION

FIG. 1 is a perspective view of a candle holder showing my new design;

FIG. 2 is an elevational view of a second embodiment of a second embodiment of my design on an enlarged scale;

FIG. 3 is an elevational view taken from the side of the first embodiment opposite that shown in FIG. 1 on an enlarged scale.

FIG. 1

FIG. 3
